UNITED STATES PATENT OFFICE.

LEVI MYERS, OF TOLEDO, OHIO.

DESIGN FOR A GAME-BOARD.

SPECIFICATION forming part of Design No. 24,771, dated October 22, 1895.

Application filed September 11, 1895. Serial No. 562,215. Term of patent 7 years.

To all whom it may concern:

Be it known that I, LEVI MYERS, a citizen of the United States, residing at Toledo, in the county of Lucas and State of Ohio, have 5 invented a new and original Design for a Game-Board, of which the following is a specification.

This invention relates to a new and original design for game-boards, and has for its 10 object to provide a design of this character that shall be both useful and ornamental.

The leading feature of the design resides in a rectangularly-shaped box provided near one end with a straight transverse partition-strip elevated above the plane of the bottom of the box and disposed parallel with one of its ends; an eccentrically-located circular-shaped figure elevated above the plane of the bottom of the box; a series of quadrant-shaped 15 figures arranged diagonally opposite the center of said circular-shaped figure and disposed above the plane of the bottom of the box at two corners thereof and at opposite ends of said partition-strip, respectively, said quadrant-shaped figures forming one of the boundaries of sector-shaped spaces; and a series of 20 parallel scalloped columns connecting the bottom of the box with the partition-strip, the circular-shaped figure, and said quadrant-shaped figures. A minor feature of the 25 design resides in short spacing-strips, arranged at one side of the partition-strip and bounding therebetween an intermediate oblong space and also inclosing small rectangular 30 corner-spaces at the corners of the box.

In the drawings, Figure 1 is a perspective view of the game-board embodying the herein-described design. Fig. 2 is a plan view of the same.

Referring to the drawings, the numeral 1 40 designates a rectangularly-shaped box provided near one end with a partition-strip 2. The partition-strip 2 is disposed above the frame of the body of the box and is arranged parallel with one of its ends. In the space at 45 one side of the strip 2 of the box is provided a circularly-shaped figure 3, located eccentric to the center of the box and elevated above the plane of the bottom thereof. Diagonally opposite the center of figure 3 are located the 50 quadrant-shaped figures 4, which quadrant-shaped spaces form one of the boundaries of the sector-shaped figures 5, located at two corners of the box and at opposite ends and one side of the strip 2. Between the strip 2 and the adjacent end of the box are arranged short spacing-strips 6, which inclose at the adjacent corners of the box rectangular spaces 7, and which bound therebetween the intermediate oblong space 8. Projected inwardly 60 into the space 8, from one end of the box 1, are a pair of parallel tapered projections 9, and the design is completed by a series of parallel scalloped columns 10, which connect the bottom of the box with the figures 3 and 4 and the strips 2 and 6. 65

What I claim is—

The design for a game board herein shown and described.

In testimony that I claim the foregoing as 70 my own I have hereto affixed my signature in the presence of two witnesses.

LEVI MYERS.
